ELECTROPERFORATION OF SHEET MATERIAL

John W. Meaker, Evanston, and Edward H. Yonkers, Jr., Glencoe, Ill.; said Yonkers, Jr., assignor to said Meaker

Application July 24, 1942, Serial No. 452,142

5 Claims. (Cl. 175—265)

This invention relates to the perforation of sheet material, having dielectric properties, by means of electric arcs. The principles of the invention may be utilized in connection with the electro-perforation of paper, leather, leatherette, patent leather, rubberized fabrics, pure gum rubber sheeting, or of any other dielectric sheet material. The material may be treated, in accordance with the present invention, as separate sheets or as a continuous web or strip. The material may be in the form of single sheets, strips or webs or in the form of a multiplicity of superposed sheets, strips, webs or plies, to be pierced simultaneously.

Any suitable apparatus may be used, in carrying out the present invention, for producing the electro-perforation of the sheet material. A particularly suitable apparatus for the purpose is disclosed in United States Patent of John W. Meaker, No. 2,372,508, issued March 27, 1945; by means of which apparatus a large number of closely spaced perforations may be made through the sheet material per unit area thereof (provided the latter is not too highly resistant to the potential arcs) with a considerable degree of uniformity of distribution, and with the sheet material moving at relatively high speed; high speed through the perforating machine being in some cases important on the grounds of economical operation, or, specifically to synchronize the perforating operation with the movement of the sheet material through other apparatus, such, for example, as bag making apparatus, in the production of perforated paper bags.

Under these, and in fact even under less exigent conditions, it has been found difficult to perforate certain types of sheet material having high dielectric strength, such as leatherette, rubberized fabrics, or even paper, especially when treated in multiple plies. At least it has been found difficult in the case of some materials to form at high speed a relatively large number of perforations per unit area evenly distributed over the given area. In the case of some materials the dielectric strength is such as to prevent the discharges from taking place unless excessively high potentials are used; or if any perforations are made, there is a tendency, as the sheet is moved through the spark gaps, for the discharges to pass through perforations already made instead of making new perforations. This may happen several times at any spark gap, depending upon the frequency of the discharges, the voltage of the current used, the dielectric strength of the sheet material, and the speed of movement of the material through the spark gaps. As a result, the perforations for a given area may be fewer in number, less uniform in size, and less uniformly spaced than is desired.

The present invention overcomes all of these

difficulties by subjecting the sheet material to a treatment, while or before being subjected to the electro-perforating operation, whereby the resistance to the electric discharges is reduced at certain definite points on the sheet material so that electro-perforation will take place at these points. Preferably this is accomplished by forming the material with pin pricks, surface breaks or ruptures (which will be referred to as "point incisions" and which may or may not be complete perforations), at definite places at which it is intended to have the electric arcs pass through and pierce the material. This procedure has several advantages: first, it reduces the dielectric strength of the material treated at the intended points of perforation, making it possible to satisfactorily electro-perforate material which has previously been found impossible, impractical or at least difficult to perforate electrically; and, second, it tends, in all materials, to prevent re-arching through perforations already made and thereby makes it possible: (1) to increase the number of perforations made per unit area; (2) to give the perforations uniform spacing or approximately any desired arrangement or pattern; (3) to increase the speed at which the material can be put through the perforating machine to effect the desired close spacing; and (4) to give the perforations more nearly uniform size. By a suitable arrangement of the point incision devices and a corresponding arrangement of the spark gaps, together with proper control of the timing of the electrical impulses impressed against said gaps, various distribution patterns of perforations may be produced. Particularly it is possible to bring about close spacing of perforations over a large area of the material in a short period of time.

The phrase "point incisions" is used to include holes, pin pricks, or other surface breaks or ruptures whether extending completely through the material or not. The incisions may, in case of some materials, be merely momentary, closing or partially closing as soon as made. The operation may involve, as in pin pricking in the case of some fabrics, only the pushing apart of the materials at given points. But, any physical disturbance of or change in the character of the material at definite points, such, for example by indentations, without actual rupture, of such character that the dielectric strength of the material is reduced at such points, is within principle of operation of the present invention.

The operation may take place either before electro-perforation or simultaneously therewith. The former method is specifically described herein and is preferred.

Preferably the reduction of dielectric strength at definite points is accomplished by mechanical means, as for example, by pins or other punctur-

ing devices, which for convenience may be fixed to a rotating drum or to rotating discs, and with which the sheet material comes into contact before it passes into the perforating machine. However, it might be effected otherwise, for example by spotting the material with a solvent or other chemical agent. The preferred mechanical operation may be described as a pin-pricking operation since the point incisions are intended to be, ordinarily, quite minute. Theoretically, and for the best results, the arrangement of the spark gaps of the electro-perforating machine and the frequencies of the electrical impulses produced at said gaps, relative to the speed of movement of the sheet material through the apparatus, should be in conformity with the distribution of point incisions made in the sheet material, so that the arcing will take place at, or approximately at, the points of such incisions. In this way a definite or approximately definite pattern or distribution of perforations may be produced. For example, the perforations may be distributed over the entire area of the sheet at substantially equal distances from each other, both in the direction of movement of the sheet and transversely thereof. The point incisions not only reduce the dielectric strength which the potential has to overcome, making possible the electro-perforation of fabrics which have been found difficult, if not impossible, to perforate electrically, but also determine, in the case of all fabrics, at least approximately, the pattern distribution of the perforations when formed.

The pin-pricking, or equivalent operation, may completely perforate the material even when a single sheet of material is treated. However, this will ordinarily not be necessary nor desirable. In the treatment of a plurality of superposed plies of sheet material, paper for example, the pin prick- ing operation may be performed so as to perforate one or more of the plies; and this may be necessary or desirable when, in the manufacture, for example, of heavy duty multi-wall paper bags, the plies are so numerous or the paper so heavy as to make their perforation by electrical discharges impossible or difficult except with excessive, perhaps, dangerously high, voltages. In any case, if the pin pricks extend completely through the sheet material, the mechanically made perforations thus produced will be changed to electric arc made perforations, by action of the electric arc, and their character radically changed.

Punched, or pin pricked perforations, particularly if minute, involve, necessarily, burrs or frayed edges around the openings. When the sheet material, the paper sheet of a bag for example, is subjected to pressure or other manipulation, the mechanically made perforations therein tend to close, wholly or partially, so that the ventilating function of such perforations is impaired or made uncertain. Moisture may also, depending upon the character of the sheet material, tend to close or partially close mechanically made perforations.

Electric arc formed perforations are burless. The holes are made by the burning away of minute portions of the material. The edges of the material around the holes are, in some cases, seared, fused or plasticized, and in all cases are more or less clearly defined in distinction to the frayed edges or burrs characteristic of mechanically made perforations. Therefore, electric arc made perforations are permanent under all conditions and their ventilating function unimpaired by pressure, moisture or other conditions.

When the pin prick- ing operation perforates the sheet material, giving burred edges, the burrs will be burned away and the edges possibly fused (depending on the character of the material) by the electric arcs.

The electric arc formed perforations may be very minute, microscopic or even sub-microscopic; or they may be large enough to be visible to the naked eye. This will depend upon the intensity and duration of the current flow through the perforation after the high tension discharge takes place. Also with high frequency impulses the perforations may be increased in diameter by repeated discharges through the same perforations.

15 In the case of material consisting of a more or less loosely woven textile fabric covered with a dense enamel coating of high dielectric strength the perforations may in some cases extend only through the coating, and not through, or entirely through, the fabric backing, at least as clearly defined perforations; and this, in fact will be all that is necessary for ventilating purposes, provided the backing has a sufficiently loose weave. The tendency however is always for the electric discharge to burn more or less clearly defined holes through the entire thickness of the fabric

The invention is illustrated in a preferred embodiment in the accompanying drawings wherein:

20 Fig. 1 is a somewhat diagrammatic plan view of an apparatus suitable for carrying out the present invention.

25 Fig. 2 is a cross sectional view in a plane passing through the set of transversely arranged spark gaps adjacent to the pin prick- ing apparatus.

30 Fig. 3 is a longitudinal sectional view which may be considered as defined by a line on Fig. 1 passing through the left-hand pin prick- ing disc and left-hand spark gap of the first group of spark gaps, and then jogged twice so as to pass through the left-hand spark gaps of the second and third sets of spark gaps successively.

35 Fig. 4 is a section, of very much exaggerated thickness, through a material difficult to perforate by ordinary methods but readily perforated in accordance with the present invention—a material such, for example, as leatherette, patent leather or rubberized fabric.

40 Fig. 5 is a similar view of the material after being initially pin pricked; and

45 Fig. 6 is a similar view of the material after electrical perforation.

50 Referring to the drawings, the sheet of material treated is indicated by letter A. It may consist of a fabric backing 10 and a dense, highly dielectric, surfacing compound 11 (Figs. 4, 5 and 6). Leatherette is a fabric of this sort; and the density and composition of the coating or surfacing material makes such fabric very difficult to perforate electrically by methods heretofore known. Other fabrics difficult to perforate by the electric arc method because of their high dielectric strength are rubber gum sheeting, patent leather, rubberized fabrics such as are used for rain coats, and elastic woven fabrics. All these fabrics may

55 be satisfactorily perforated by employment of the present invention. When rubber sheeting is perforated by this method, the initial pin pricks appear to close up as soon as the pins are withdrawn. Nevertheless, the dielectric strength has been reduced by the pin prick- ing operation so as to provide paths of reduced resistance for the electric arcs.

60 Referring again to the drawings, B designates, generally, the pin prick- ing device, and C the electro-perforating mechanism. The sheet of mate-

rial A may be moved, continuously, and guided through the pin pricking apparatus B, and then through the spark gaps of the electro-perforating machine by feed rollers 12, 12 and guide rollers 13, 13. As shown, the pin pricking apparatus B consists of a supporting roller 14 which may, if desired, be spring mounted, and of a plurality of discs 15, 15¹, 15², 15³, 15⁴, 15⁵, 15⁶, 15⁷, 15⁸ on shaft 16, which discs are provided, in circumferential arrangement, with pointed pins 17. The discs may be either fixed to or rotatable on shaft B which latter may, if the discs are fixed thereto, be revolved either by driving means or by contact with the moving sheet material. The pins, in the arrangement shown, do not perforate the sheet of material, although they might do so, but merely make surface incisions, breaks or indentations therein which are indicated at a Figs. 1, 2, 3 and 5. The shaft may be mounted so as to be vertically adjustable for fabrics of different thicknesses.

The electro-perforating apparatus C comprises, as shown in the drawings, three sets of electrodes, each set consisting of three pairs of opposed electrodes in series with each other and with the secondary coils of three transformers, respectively. The number of electrodes in each set may, of course, be increased or decreased; and also the number of sets of electrodes. The pairs of electrodes of one set are preferably staggered with respect to the pairs of electrodes of the other sets. The pairs of electrodes are approximately in line with the pin pricking discs 15-15⁸.

Referring particularly to Figs. 1, 2 and 3, the pairs of electrodes of the first set of electrodes are designated 18, 18', 19, 19' and 20, 20'. They are shown as supported by bars of insulating material 21, 21' and are connected by wires 22, in series with each other and with the secondary coil 23 of a transformer, designated D, as a whole, the primary coil of which 24 is connected to the supply leads 25.

In the arrangement shown, the electrodes 18, 18' are aligned with the disc 15; the electrodes 19, 19' with the disc 15³; and the electrodes 20, 20' with the disc 15⁶. In the next set of electrodes, designated 26 as a whole, the electrodes 27, 28 and 29, and, of course, the complementary electrodes beneath the material treated, are in line with the discs 15¹, 15⁴ and 15⁷, respectively. These electrodes are in series with each other and with the secondary coil 23 of the transformer E. The electrodes 30, 31 and 32, and their complementary electrodes, forming the third set of electrodes 33, are in line with the discs 15², 15⁵ and 15⁸, respectively, and are in series with each other and with the secondary coil 23 of the transformer F. Transformers E and F are connected to the supply leads 25 so that the transformers D, E and F are in parallel.

By this arrangement, and by suitable control of the timing of the electric discharges relative to the speed of movement of the sheet of material treated, the point incisions or pin pricks a made by the discs 15-15⁸ are brought into or near the gaps between the electrodes in such time relation with the electrical impulses in the electrode circuits that the discharges arc through the material at the pin pricks a so that said pin pricks are, by action of the impulses, formed into electric arc made perforations b. The reason for having a plurality of sets of staggered spark gaps, instead of a single set of spark gaps arranged close together, is that the latter arrangement involves the danger of the current jumping from

one electrode to an adjacent electrode on the same level instead of across the intended spark gaps and through the sheet material moving through said gaps. There are also mechanical difficulties in arranging the pairs of electrodes too close together.

The perforating apparatus may employ direct currents, interrupted at the proper intervals by suitable make and break devices. Or the apparatus may be supplied from an alternating current source, such as a generator, controlled so that discharges will take place between opposed electrodes while the point incisions are between or near to said electrodes. Obviously, the frequencies in the case of alternating currents may be higher than required by the point incision pattern. That is, several alternations of current may take place through the same perforation while the sheet of material is in motion. In some cases the current may be interrupted by the continued movement of the sheet and consequently several alternations of potential may take place without any discharges through the material. In such cases discharges may occur at points of low dielectric strength other than at the incision points. This may be regarded as accidental.

For mechanical reasons it is desirable to employ frequencies sufficiently high so that synchronism with the point incision pattern is not essential.

While the invention has been described in a preferred embodiment, it will be understood that it is not to be considered as so limited. The intention is to cover all equivalents and also all modifications within the scope of the hereto appended claims.

While the apparatus, as shown and described, is designed so as to provide a distribution of perforations over the entire area of the sheet of material treated, with the perforations substantially equi-distant from each other and close together, and it is one of the objects of the invention to make practical such distribution of perforations through material difficult to perforate electrically in such manner, the invention is not limited thereto. Obviously, by proper design and arrangement of the pin prickling devices and of the perforating electrodes, various patterns of perforations may be produced. For the purpose of simplified showing, only three sets of electrodes are illustrated. The number may be increased to five or six or more, while maintaining the staggered relation between all sets, with the result that the perforations will be closer together, transversely of the sheet, than is indicated in Fig. 1.

In case frequencies are employed higher than that represented by the time required to move the sheet the distance between pin pricks (which is desirable for the reasons above stated), and in case the dielectric strength of the material, as a whole or in places, be such as to permit perforation at points other than at the pin pricked points, the perforation pattern indicated in Fig. 1 might, as stated, be modified by additional perforations irregularly distributed with reference to the intended pattern. In most instances this would be a matter of no importance and might be an advantage because resulting in the production of a larger number of perforations per unit area than would otherwise be the case. The expedient of pin prickling the material at definite points would insure, in any event, a desired minimum number of perforations per unit area. In many cases this is the most important desideratum. If

each unit area be assured of being perforated with a minimum number of perforations, a few more perforations would ordinarily involve no disadvantage. In other words, a definite pattern may be produced if desired, or a minimum of perforations per unit area may be assured with the possibility of additional, irregularly distributed perforations, in accordance with the character of the material treated and the manner in which the apparatus is designed and controlled. In any case, the arcs, or some of them, are directed through the material treated at definite points at which the dielectric strength of the material has been reduced by the pin prickling operation. This mode of operation makes possible, first, the electro-perforation of materials, such as leatherette for example (or other difficultly perforable materials mentioned above), the dielectric strength of which is such as to make electro-perforation, by methods heretofore used, impossible or impractical, at least when a large number of perforations closely spaced together is the requirement; second, it makes possible the certainty that, for any type of fabric, a minimum number of perforations will be made per unit area; and third, it makes possible a distribution of the perforations in a predetermined pattern if such be desired.

In the perforation of fabrics having coatings of enamel it is often necessary to make a slight rupture only in the surface of the enamel in order to effect a very considerable reduction in dielectric strength. The reduction in dielectric strength is frequently out of all proportion to the depth of the incision.

By the term "arc," as used herein, is meant an ionized path of a relatively low electrical resistance extending continuously between electrodes, in distinction to a brush or corona discharge or similar phenomenon. Such ionized path permits the passage of the relatively high currents which are necessary for producing perforations of the desired diameter and performance.

It has been found possible, by using the method hereinabove described, to perforate material such as leatherette with a large number of perforations per unit area and with the material moving through the apparatus at a fairly high rate of speed. By methods heretofore used it was not possible, or at least practical, to electrically perforate materials of this character. A few scattered perforations may be made, but it has not been found possible (except, perhaps, by a very slow operation) to form enough perforations to provide, say, any effective ventilating function. With applicants' present invention it is possible to make as many as sixty-four or more perforations per square inch in material of this sort. If leatherette is formed with say from sixteen to sixty-four perforations per square inch, the perforations will have an appreciable ventilating function. The size of the perforations, on the average, may vary from two to four thousandths of an inch in diameter. These figures are, of course, purely illustrative. The perforations may be minute enough so that water will not pass therethrough except under considerable pressure. When desired, they may be so small as to be practically invisible to casual observations at least. The perforations may be large enough or numerous enough to have an effective ventilating func-

tion without appreciably affecting the strength of the sheet material.

We claim:

- 5 1. Apparatus for electro-perforation of dielectric sheet material which comprises in combination: rotatable pin-pricking devices; a plurality of pairs of electrodes providing spark gaps; means for moving said sheet material in contact with said pin-pricking devices, to form point incisions therein, and thereafter for moving the material through said spark gaps; and means for causing high potential electric currents to discharge across said spark gaps and through said material at said point incisions.
- 10 15 2. Apparatus for electro-perforation of dielectric sheet material which comprises in combination: rotatable pin-pricking devices; a plurality of pairs of electrodes providing spark gaps substantially in line with said pin-pricking devices, respectively; means for moving said sheet material in contact with said pin-pricking devices, to form point incisions therein, and thereafter for moving said material through said spark gaps; and means for causing high potential electric currents to discharge across said spark gaps and through said material at said points of incision.
- 20 25 3. Apparatus for electro-perforation of dielectric sheet material which comprises in combination: a plurality of series of sets circularly arranged, rotating pin-pricking devices; a plurality of pairs of electrodes forming spark gaps which are in substantial alignment with said series of pin-pricking devices, respectively; means for moving said sheet material in contact with said 30 35 pin-pricking devices, to form point incisions therein, and then through said spark gaps; and means for causing electrical discharges to arc across said spark gaps and through the material at said points of incision.
- 40 4. Art of obtaining closely spaced perforations in sheet material having high dielectric strength which comprises reducing the dielectric strength of the material at a plurality of predetermined points by penetrating the sheet from one surface 45 a distance less than the thickness of the sheet whereby the dielectric strength of the sheet is weakened and the tendency, as the sheet is subsequently moved through arcs, for the discharges to pass through perforations already made instead of making new perforations, is prevented, and substantially immediately thereafter causing electrical discharges to arc through the material at such points to form electric arc made perforations.
- 50 5. Art of obtaining closely spaced perforations in sheet material having high dielectric strength which comprises reducing the dielectric strength of the material at a plurality of predetermined points by making point incisions in the sheet from one surface a distance less than the thickness of the sheet whereby the dielectric strength of the sheet is weakened and the tendency, as the sheet is subsequently moved through arcs, for the discharges to pass through perforations already made instead of making new perforations, is prevented, and substantially immediately thereafter causing electrical discharges to arc through the material at such points to form electric arc made perforations.
- 60 65 70
